FUSE CONSTRUCTION

William O. Schultz, South Milwaukee, Wis., assignor to Line Material Company, South Milwaukee, Wis., a corporation of Delaware

Application August 31, 1936, Serial No. 98,648

16 Claims. (Cl. 200—114)

This invention relates to a fuse construction and is particularly directed to a fuse construction associated with a transformer or other electrical device.

5 This invention is intended to provide a fuse construction which is particularly useful on a single bushing transformer which is now quite common for rural service. These transformers are made up with only one primary bushing, the 10 other side of the primary winding being solidly grounded to the transformer case.

Objects of this invention are to provide a fuse construction in which the fuse structure is carried by or supported from the transformer bushing, in which only moderate stresses are imposed 15 on the bushing and the bushing is thus relieved of undue strains, in which the fuse is so mounted that the expelled gases and metallic vapors are directed away from the casing particularly as the 20 fuse moves to inoperative position, and in which an expulsion type of drop-out fuse is provided.

Further objects are to provide a construction in which an expulsion type of drop-out fuse is 25 readily applied to or removed from any of the usual types of single bushing transformers, in which provision is made for detachably locking the base of the fuse construction to the conducting stud or member carried by the transformer bushing so that the base and stud jointly 30 form a portion of the electrical circuit to the transformer.

Further objects are to provide a fuse construction in which the fuse is so mounted that it is biased by gravity to drop to inoperative 35 position when released by the fuse link, in which no springs are employed, and in which a very simple and cheap construction is obtained.

Further objects are to provide a construction 40 in which the drop-out fuse is so mounted and so constructed that it may be manually moved to open position while the fuse link is intact, and in which the fuse tube may be operated by a fuse stick without requiring the operator or lineman to get above the transformer but allowing him 45 to operate the fuse while the lineman is supported on a pole at a considerable distance below the fuse tube, thereby avoiding danger of the lineman coming in contact with transformer lead wires and overhead feeder wires, and thus allowing the lineman to operate the fuse tube without 50 having to assume any abnormal positions.

Further objects are to provide a fuse construction 55 for transformers in which surge protection is provided so that when the fuse blows, the transformer is nevertheless protected against

surges as an arcing gap is provided independently of the position of the fuse tube.

The different manufacturers of single bushing 5 transformers position the arcing tip, which is carried by the casing of the transformer, at different distances and different positions with respect to the bushing.

This invention is designed to provide a fuse construction in which an adjustable arcing horn is provided, which has both motion of translation 10 and motion of rotation, that is to say, in which the arcing horn may be pulled out or pushed back with reference to its support or may be rocked about a pivot point so as to accurately align the arcing horn with the arcing tip. 15

Embodiments of the invention are shown in the accompanying drawings, in which:

Figure 1 is a side elevation with parts broken away and in section showing the fuse construction applied to a single bushing transformer, a 20 fragment of the transformer casing being shown.

Figure 2 is a similar view taken at right angles to Figure 1.

Figure 3 is a plan view of the fuse structure.

Figure 4 is a sectional view on the line 4—4 of 25 Figure 2.

Figure 5 is a plan view showing a further type of arcing horn.

Referring to the drawings, it will be seen that the metallic transformer casing has been indicated by the reference character 1 and the insulating bushing by the reference character 2. The transformer stud or terminal 4' is threaded and projects through the bushing 2 and receives a cap nut 4 which is provided with an integral 30 stud 3. The cap nut 4 and its integral stud 3, therefore, constitute the terminal portion of the transformer. The stud 3 is thus rigid with the bushing. The casing 1 is also provided with an arcing tip 5 which may consist of an upwardly 35 projecting rod carried by the casing.

The fuse construction includes a metal base portion 6 which is socketed and fits over the stud 3 and is locked to the stud by means of a set screw 7, see Figure 4. Preferably the socket has 45 a relatively tapered aperture indicated at 8, as in Figure 4, to allow the socket to take different sizes of studs and to wedge the stud in place when the set screw 7 is tightened, to thus provide a rigid supporting means for the fuse construction. 50

The base is provided with a laterally extending arm 9 integral therewith and provided with a pivot portion 10 headed as indicated at 11 in Figure 3. The arm 9 is also provided with a 55

rearwardly projecting overhanging stop member 12 which limits the rocking of the supporting lever for the fuse tube, as will hereinafter be described.

- 5 The base 6 carries an insulator 13 which projects upwardly therefrom and is provided with an upper terminal member 14. This terminal member is provided with an arm 15 that projects laterally therefrom and is equipped with a sleet 10 hood 16 provided with divergent side portions, as shown in Figure 3, which serve to assist in guiding the upper end of the fuse tube into place when it is being rocked to closed position.

The terminal member 15 is also provided with 15 a tying eye 17. Within the sleet hood a contact member 18 in the form of a spring arm is provided and is secured as indicated at 19 interiorly of the sleet hood. This contact member or arm is apertured and is provided with an upwardly 20 turned cam portion 20 and with an outwardly slanted guiding lip 21.

The contact member 18 projects downwardly below the inner end of the sleet hood and receives a connector 22 by means of which the line wire 25 23 may be secured thereto. The line wire thus is directly attached to the upper contact. If the distance between the point of support of the line wire and the fuse is great, the line wire may be tied to the tying member 17, as shown in Figure 1. Otherwise it may extend directly to the upper contact member.

The fuse is of the drop-out expulsion type and comprises a fuse tube 24 having an upper contact or terminal 25 which includes a clamping cap 35 26 provided with an upwardly extending projection 27 normally fitting within the recess of the contact member 18 and beyond the lip 20, as shown in Figure 1. This upper cap clamps the button of the fuse link to the upper terminal of 40 the fuse. The member 25 is preferably provided with a pull ring 28 integral therewith and projecting outwardly therefrom. The fuse link may comprise the fusible portion 29 and the leader 30, the leader projecting outwardly through the 45 lower open end of the fuse tube.

Mechanism in the form of a bell crank lever 31 is provided and is pivotally joined to the fuse tube and to the support. The fuse tube is provided with a collar 32 which has rearwardly 50 projecting ears 33 and the lever 31 is pivotally joined to the ears 33 by means of the pin 34.

The lever is provided with a pair of hooked arms 35 which hook over the pivot 10 and thus allow the fuse to be detached from the pivot 55 during refusing after the fuse has rocked downwardly. The lever 31 is limited in its rocking motion by the support 12. The lever 31 is provided with a portion or arm 36 provided with a thumb nut 37 by means of which the leader 30 60 of the fuse link may be locked to the lever, so that the lever is restrained from releasing motion by the fuse link. It is clear that when the fuse link blows, the lever 31 will be released and will rock about the pivot portion 10 and thus 65 lower the upper end of the fuse from the upper latch or contact 18, thus disengaging the upper end of the fuse tube and allowing it to rock into the dotted line position. Preferably a pin 38 is carried by the base portion 6 for limiting the downward motion of the fuse tube.

70 It will be seen that the open end of the fuse tube rocks away from the casing of the transformer and away from the bushing and thus directs the discharging gases and metallic vapors 75 away from the casing.

Further than this, it is apparent that the pivot point is mounted closely adjacent the bushing and that the pivot point and upper contact or latch are mounted on opposite sides of a plane passing through the axis of the bushing. Consequently when the fuse tube is pulled downwardly, as by means of a fuse stick or switch stick inserted in the eyelet 28, there is no great strain placed on the insulator or bushing.

Further than this, it is apparent that the operator can reach the fuse tube with a switch stick while the operator is below the transformer and may pull the device open by a substantially downwardly directed pull, thus avoiding the necessity of the operator climbing above the transformer into the relatively dangerous zone of feeder wires, etc., and also allowing the operator to open the device without requiring him to assume any abnormal or inconvenient positions.

The fuse tube is biased by gravity towards in- 20 operative position and no springs are required for the operation of the device.

It is to be noted particularly from Figures 2 and 3, that the upper terminal member 14 is provided with an arm 39 projecting laterally therefrom and carrying a locking bolt 40. An arcing horn 41 is provided and is preferably slotted, as indicated at 42, to receive the locking bolt 40. This arcing horn has a downwardly extending portion 43, see Figure 2, which is aligned 30 with the arcing tip 5. It is clear that the arcing horn may be moved in or out or may be rocked about the locking bolt 40 so as to accurately align the arcing horn with the arcing tip. It is obvious that the arcing horn may take other 35 forms. For example, it may be of a rod construction, as indicated at 44, and may be provided with a rearwardly bent portion 45 to provide the slot 46.

It will be seen that the device is very simple 40 in construction, that it is cheap to make, that it will fit many different types of transformers.

Although this invention has been described in considerable detail, it is to be understood that such description is intended as illustrative rather 45 than limiting, as the invention may be variously embodied and is to be interpreted as claimed.

I claim:

1. In a circuit interrupter, a fuse structure, an insulating bushing, means supporting said fuse structure from said bushing, said fuse structure including a tube having an open lower end and movable from operative to inoperative position, a fuse link in said fuse tube, and restraining means controlled by said fuse link normally holding said fuse tube in operative position and releasing said fuse tube for motion towards inoperative position when said fuse link is ruptured, the open end of said fuse tube moving away from said bushing when said fuse link is ruptured, whereby the discharge from the open end of said fuse tube is directed away from said bushing.

2. In a circuit interrupter, a fuse structure, an insulating bushing, means supporting said fuse structure from said bushing, said fuse structure 65 including a tube having an open end and movable from operative to inoperative position, a fuse link in said fuse tube, said fuse tube being biased by gravity towards inoperative position, and restraining means controlled by said fuse link normally holding said fuse tube in operative position and releasing said fuse tube for motion towards inoperative position when said fuse link is ruptured, the open end of said fuse tube moving away from said bushing when said fuse link is 70 ruptured.

ruptured, whereby the discharge from the open end of said fuse tube is directed away from said bushing.

3. In a circuit interrupter, an insulating bushing, a drop-out fuse structure supported from said bushing and including a pivotally mounted fuse tube movable from operative to inoperative position, mechanism normally holding said fuse tube in operative position and releasing said tube when said mechanism operates, and a fuse link restraining said mechanism from releasing operation, said fuse tube being biased by gravity towards inoperative position.

4. In a circuit interrupter, an insulating bushing, anchor means carried by said bushing, a fuse structure including a base portion detachably secured to said anchor means and forming with said anchor means a part of an electrical circuit, a fuse tube movably supported from said base portion and movable from operative to inoperative position, and a fuse link normally restraining said tube against motion, said fuse being manually movable from operative to inoperative position by a substantially downwardly directed pull.

5. In a circuit interrupter, an insulating bushing, anchor means carried by said bushing, a drop-out fuse structure including a base portion detachably secured to said anchor means and forming with said anchor means a part of an electrical circuit, a fuse tube pivotally supported from said base portion, an upper latch means for said fuse tube, and a fuse link within said fuse tube normally restraining said fuse tube against pivotal motion, said fuse tube when released by said fuse link moving from operative position to inoperative position away from said upper latch means, said fuse tube being releasable from said upper latch means by a substantially downwardly directed pull while said fuse link is intact.

6. In a circuit interrupter, an insulating bushing, anchor means carried by said bushing, a drop-out fuse structure including a base portion detachably secured to said anchor means and forming with said anchor means a part of an electrical circuit, a fuse tube pivotally supported from said base portion, an upper latch means for said fuse tube, said fuse tube slanting downwardly from said upper latch means, whereby said fuse tube tends to drop downwardly when released from said upper latch means, and a fuse link within said fuse tube normally restraining said fuse tube against pivotal motion, said fuse tube when released by said fuse link moving from operative position to inoperative position away from said upper latch means, said fuse tube being releasable from said upper latch means by a substantially downwardly directed pull while said fuse link is intact.

7. In a circuit interrupter, an insulating bushing, anchor means rigidly carried by said bushing, a fuse structure including a base portion detachably locked to said anchor means for supporting said fuse structure and forming with said anchor means a part of an electrical circuit, said base portion having a pivot portion located adjacent said bushing, a fuse tube pivotally supported from said pivot portion and normally projecting upwardly therefrom, an upper latch means for said fuse tube, said fuse tube being biased towards downward rocking motion away from said upper latch means, and a fuse link normally restraining said fuse tube against motion.

8. In a circuit interrupter, an insulating bush-

ing, anchor means rigidly carried by said bushing, a fuse structure including a base portion detachably locked to said anchor means for supporting said fuse structure and forming with said anchor means a part of an electrical circuit, said base portion having a pivot portion located adjacent said bushing, a fuse tube pivotally supported from said pivot portion and normally projecting upwardly therefrom, an upper latch means for said fuse tube, said fuse tube being biased towards downward rocking motion away from said upper latch means, and a fuse link normally restraining said fuse tube against motion, said pivot portion and said latch means being located on opposite sides of a plane passing through the axis of said bushing.

9. In a circuit interrupter, an insulating bushing, a fuse structure including a base and an upper contact, a fuse tube movably supported from said base and biased towards motion downwardly away from said upper contact, a fuse link within said fuse tube normally restraining said fuse tube against motion, and a support carried by said insulating bushing, said base and said support holding said fuse tube above the top of said insulating bushing, said fuse tube being manually movable away from said upper contact by a substantially downward pull and being reachable with a fuse stick passed upwardly.

10. In an apparatus of the class described, an electrical device provided with a metal casing, said casing having an arcing tip, an insulating bushing carried by said casing, a fuse structure for protecting said electrical device supported from said bushing and having a base locked with respect to said bushing, a fuse tube movably supported from said base and biased towards motion from operative to inoperative position, an insulator carried by said base, a contact carried by said insulator, a fuse link normally electrically connecting said contact and said base and restraining said fuse tube against motion, and an arcing horn adjustably supported from said insulator and connected to said contact.

11. In an apparatus of the class described, an electrical device provided with a metal casing, said casing having an arcing tip, an insulating bushing carried by said casing, a fuse structure for protecting said electrical device supported from said bushing and having a base locked with respect to said bushing, a fuse tube movably supported from said base and biased towards motion from operative to inoperative position, an insulator carried by said base, a contact carried by said insulator, a fuse link normally electrically connecting said contact and said base and restraining said fuse tube against motion, and an arcing horn adjustably supported from said insulator and connected to said contact, said arcing horn having both translatory and rocking motion, whereby said arcing horn may be aligned with said arcing tip.

12. In a circuit interrupter, an insulating bushing, a fuse structure including a base supported from said bushing, said base having a pivot portion, a drop-out fuse tube, an upper contact, a lever pivoted to said fuse tube and said pivot portion and normally holding said fuse tube in engagement with said upper contact and adapted to release said fuse tube, said fuse tube being biased towards downward motion away from said upper contact, and a fuse link normally holding said lever against releasing motion.

13. In a circuit interrupter, a bushing, anchor means rigidly carried by said bushing, a fuse

75

- structure including a base portion detachably locked to said anchor means for supporting said fuse structure and forming with said anchor means a part of an electrical circuit, said base portion having a pivot portion located adjacent said bushing, a fuse tube pivotally supported from said pivot portion and normally projecting upwardly therefrom, and an upper latch means for said fuse tube, said pivot portion and said latch means being located on opposite sides of a plane passing through the axis of said bushing.
14. In an apparatus of the class described, an electrical device having a casing provided with a top portion and side walls, a fuse structure for protecting said electrical device and including a base and an upper contact, a fuse tube movably supported from said base, and a support carried by and insulated from said casing, said base and said support holding said fuse tube above the top of said casing and above and adjacent a side wall of said casing, said fuse tube being manually movable away from said upper contact and being reachable with a fuse stick passed upwardly adjacent a side wall of said casing.
15. In an apparatus of the class described, an electrical device having a casing provided with

a top portion and side walls, a fuse structure for protecting said electrical device and including a base and an upper contact, a fuse tube movably supported from said base, and a support carried by and insulated from said casing, said base and said support holding said fuse tube above the top of said casing and above and adjacent a side wall of said casing, said fuse tube being manually movable away from said upper contact by a substantially downward pull and being reachable with a fuse stick passed upwardly adjacent a side wall of said casing.

16. In an apparatus of the class described, an electrical device provided with a metal casing, said casing having an arcing tip, an insulating bushing carried by said casing, a fuse structure for protecting said electrical device supported from said bushing and having a base locked with respect to said bushing, a fuse tube supported from said base and normally connecting an upper and a lower contact, and an arcing horn adjustably supported from said upper contact, said arcing horn having both translatory and rocking motion, whereby said arcing horn may be aligned with said arcing tip.

WILLIAM O. SCHULTZ.
